UNITED STATES PATENT OFFICE.

MAX BRILL, OF NEW YORK, N. Y.

DESIGN FOR A HAND BAG.

Application filed April 7, 1922. Serial No. 1,627. Term of patent 3½ years.

To all whom it may concern:

Be it known that I, MAX BRILL, a citizen of the United States, and resident of the borough of Manhattan, city, county, and State of New York, have invented a certain new, original, and ornamental Design for Hand Bags, of which the following is a specification, reference being had to the accompanying drawing, forming part thereof.

In the drawing,

I claim;

The ornamental design for a handbag as shown.

MAX BRILL.
